COMBINED HAIR CURLER AND COMB

Anne Wood Cournoyer, Medford, Mass.

Application December 8, 1950, Serial No. 13,339

Term of patent 3½ years

(Cl. D86—8)

To all whom it may concern:

Be it known that I, Anne Wood Cournoyer, a citizen of the United States, residing at Medford, county of Middlesex, and Commonwealth of Massachusetts, have invented a new, original, and ornamental Design for a Combined Hair Curler and Comb, of which the following is a specification, reference being had to the accompanying drawing, forming a part hereof.

In the drawings:

Fig. 1 is a side elevational view of a combined hair curler and comb embodying the new and ornamental design;

Fig. 2 is an end view looking from the left with reference to Fig. 1; and

Fig. 3 is an end view looking from the right with reference to Fig. 1.

I claim:

The ornamental design for a combined hair curler and comb, substantially as shown.

ANNE WOOD COURNOYER.
